UNITED STATES PATENT OFFICE.

LESTER A. GRIMES, OF MONTCLAIR, NEW JERSEY, ASSIGNOR TO GRIMES SPRINKLER COMPANY, INC., OF NEWARK, NEW JERSEY, A CORPORATION OF NEW JERSEY.

ROTARY ALARM DEVICE.

Application filed June 25, 1925. Serial No. 39,435.

The present invention relates primarily to mechanical alarm devices used in connection with automatic sprinkler systems for the putting out of fires.

Such devices ordinarily comprise a water motor connected with the sprinkler system, and a gong actuated by the motor. Usually the motor is installed within the building, and the gong on the exterior in order that the alarm may be heard throughout the neighborhood in the event of fire. Such installations necessitate the making of a hole through the building wall; and experience has shown that it is difficult to get the motor and gong so aligned and positioned on opposite sides of the wall that the driving shaft connection between the two will at all times run true.

One object of the present invention is the provision of means whereby accurate alignment becomes non-essential; this is accomplished by a universal joint connection between the driving shaft and the shaft of the motor, and a connection between the other end of the driving shaft and the knocker arm of the gong by which the shaft may have a substantial degree of lateral movement, to adjust itself to out-of-alignment positioning, while the knocker arm is securely held in an immovable bearing.

Another object is the provision of means whereby the motor and gong may be quickly put in place on opposite sides of the wall and fixedly secured in position.

The accompanying drawings are for the purpose of illustrating means for accomplishing these objects, but it is to be expressly understood that they are not to be taken as defining the limits of the invention, reference being had to the appended claims for that purpose. In the drawings—

Fig. 1 is a vertical section of the device as a whole installed in position;

Fig. 2 is an enlarged vertical section of the knocker arm and its support; and

Fig. 3 is a front elevation taken from the right of Fig. 2.

In the embodiment of the invention as shown in the drawings, A is the wall of the building in which the sprinkler system is installed. The water motor B, of any suitable type, is carried by the frame-work C. An opening D in the frame is screw-threaded to

engage the pipe E, the latter being externally threaded at each end. This pipe extends through the wall, and at its outer end is covered by the cap F.

The gong G is protected by the cover plate H, both being held in place by the bolt J supported by the frame I. This frame is provided with an opening K through which the pipe E projects to receive its cap F. When the cap is in position, its inner edge contacts with the frame I, and by turning the cap down tightly both the motor and the gong are securely held as shown.

The knocker arm L has a slot M at each end to receive the knockers N—N', each knocker being loosely mounted on a shaft O positioned transversely to the slot and supported by the arm. When the knocker arm is set in motion, the knockers are thrown outward by centrifugal force to the point where they strike the gong and sound the alarm.

The knocker arm is provided with a hollow shaft P, the two being preferably integrally cast, which shaft rotates in the bearing Q. This bearing is externally threaded at its outer end to engage an internally threaded centrally located opening in the cap F. The shaft P projects inwardly beyond its bearing Q, and at its inner end is provided with a ring R secured in position as by the pin S, to prevent the shaft from having outward axial movement. The bearing Q is preferably internally recessed as at T to provide space for a lubricant.

Midway between its ends the knocker arm L is provided with a centrally apertured recess U into which is loosely fitted the key V. The driving shaft W is connected at its inner end to the shaft of the motor by a universal joint X of any suitable construction. The other end of the driving shaft passes freely through the bore of the shaft P, on through the aperture in the recess U, and at its outer end takes the key V, the latter being securely held in place on the shaft as by the set screws Y. The aperture in the recess U is concentric with the bore of shaft P, and may be provided with a somewhat rounded side wall, as shown, to serve as a fulcrum for the driving shaft. If not so shaped, or sufficiently thin to serve as a fulcrum, the aperture should be of a diameter somewhat greater than that of the

shaft to permit slight lateral movement of the shaft.

The construction and arrangement of parts is such that no special degree of care need be exercised in making the opening through the wall nor in positioning the parts; the motor and gong may be quickly put in place and securely fixed, and the driving shaft will take any position necessary to compensate for out-of-alignment relation between the motor and gong,—the universal joint at the inner end of the driving shaft permitting a certain degree of angularity between the axis of that shaft and the axis of the motor shaft, and the outer end of the driving shaft being free to permit of a certain degree of sidewise movement because of the play permitted between the key and its recess in the knocker arm. As a further aid to quick assembly of the parts, the driving shaft need not be of an accurately predetermined length,—care being taken only to have it sufficiently long to take on the knocker and key. When the installation is complete, except for putting in place the gong 25 and its cover, any extra length of shaft can be readily cut off just beyond the key.

It will be observed that the pipe E serves not only as a means for securing the motor and gong in place and in fixed relation with each other, but also as a protective covering for the driving shaft; further, while the knocker arm rotates on a fixed axis with relation to the gong, its connection with the driving shaft is such as to permit lateral play of the shaft and its automatic adjustment to compensate for out-of-alignment positioning whereby the driving shaft is at all times freely revoluble and positive in its actuation of the knocker.

Having thus described the invention, the following is claimed:

1. In a device of the character described, a water motor and a gong in combination with means for retaining the same in position, a knocker arm having therein a centrally apertured recess, a bearing carried by said retaining means, a shaft for said knocker arm arranged to rotate in said bearing, a driving shaft connected with said motor and freely passing through said aperture, and a key secured to said shaft and loosely fitting within

said recess and arranged to rotate said knocker arm.

2. In a device of the character described, a water motor and a gong, in combination with means for retaining the same in position, a knocker arm and a shaft therefor, a bearing carried by said retaining means and arranged to receive said shaft, and a driving shaft self-adjusting throughout its entire length extending through said retaining means and connecting said motor and knocker arm. 55 60

3. In a device of the character described comprising a water motor and a gong, in combination with means for retaining the same in position, a bearing carried by said retaining means, a knocker arm, a shaft connected with said arm and arranged to rotate in said bearing, a driving shaft extending through said retaining means and said knocker arm shaft but not in contact therewith, and a lost motion connection between said driving shaft and said knocker arm. 65 70

4. In a device of the character described comprising a water motor and a gong, in combination with means for retaining the same in position, a bearing carried by said retaining means, a knocker arm, a shaft connected with said arm and arranged to rotate in said bearing, a driving shaft extending through said retaining means, and means at each end of said shaft arranged to connect respectively with the motor shaft and the knocker-arm and to compensate for out-of-alignment positioning of the motor and gong. 75 80

5. In a device of the character described, comprising a water motor and a gong operated thereby and designed to be positioned on the opposite sides of a wall, a pipe adapted to pass through the wall and to be connected with said motor to support the same, means attached to said pipe for retaining the gong in position, a knocker arm and a shaft therefor, bearings for said shaft carried by said retaining means, and a driving shaft within said pipe connected at one end to the water motor shaft and at the other end to the knocker arm. 85 90 95

In testimony whereof, I have signed my name to this specification.

LESTER A. GRIMES.
